United States Patent Office

Des. 209,880
Patented Jan. 9, 1968

209,880

REFLECTING TRAFFIC GUIDE OR SIMILAR ARTICLE

Roger G. Royer, Parkersburg, W. Va., assignor to Borg-Warner Corporation, Chicago, Ill., a corporation of Illinois

Filed Nov. 16, 1966, Ser. No. 4,686

Term of patent 14 years

(Cl. D72—1)

FIG. 1

FIG. 2

FIG. 3

FIGURE 1 is a top plan view of a reflecting traffic guide or similar article showing my new design; and

FIGURE 2 is a side elevational view thereof; and
FIGURE 3 is a front elevational view thereof.

I claim:

The ornamental design for a reflecting traffic guide or similar article, substantially as shown.
